US00D681615S

(12) **United States Design Patent**
Fathollahi

(10) **Patent No.:** **US D681,615 S**
(45) **Date of Patent:** **** May 7, 2013**

(54) **CASE**

(75) Inventor: **Andy Fathollahi**, Corona Del Mar, CA
(US)

(73) Assignee: **Incipio Technologies, Inc.**, Irvine, CA
(US)

(**) Term: **14 Years**

(21) Appl. No.: **29/385,458**

(22) Filed: **Feb. 14, 2011**

(51) **LOC (9) Cl.** **14-03**

(52) **U.S. Cl.**

USPC **D14/250**

(58) **Field of Classification Search** D14/248,

(57) **CLAIM**

I claim the ornamental design for a case, as shown and described.

DESCRIPTION

FIG. 1 is a top end view of a case;
FIG. 2 is a bottom end view thereof;
FIG. 3 is a left side view thereof;
FIG. 4 is a right side view thereof;
FIG. 5 is a front view thereof;
FIG. 6 is a rear view thereof; and,
FIG. 7 is a rear perspective view of the case.
The broken lines are for illustrative purposes only and form no part of the claimed design.
